UNITED STATES PATENT OFFICE

EUGENE F. CLARK, OF DAMARISCOTTA, MAINE, ASSIGNOR TO MARSHALL FIELD MILLS CORPORATION, OF PHILADELPHIA, PENNSYLVANIA, A CORPORATION OF PENNSYLVANIA

LOOM FOR WEAVING TUFTED PILE FABRIC

Application filed January 10, 1930. Serial No. 419,765.

This invention relates to improvements in that class of looms for weaving tufted pile fabric wherein tuft yarn frames or carriers, commonly called tube frames, are mounted in spaced parallel relation on a pair of endless carrying chains which are actuated to bring the frames successively into a yarn delivering position, and wherein a row of yarn grippers are supported and actuated to move from a position adjacent to the fell of the fabric being woven to a position adjacent to the yarn delivering position of the tuft yarn frames and back again to receive the tuft yarn from the frames and transfer it to the fabric, as illustrated and described in my previous Patent No. 1,594,605, dated August 3, 1926.

The object of my present invention is to improve the construction of the tuft yarn frames as related to the yarn grippers whereby the grippers, during the operation thereof may enter yarn passages of the frames to receive the tuft yarns therefrom without danger of having parts of the grippers engage parts of the frames and damage either the grippers or the frames even though some or all of the grippers might not be in perfect registry with the yarn passages when the grippers are moved into the same.

The invention consists of the elements and the combinations of them hereinafter described and claimed.

In the accompanying drawings illustrating the invention,

Figure 1 is a vertical section through a portion of a loom for weaving tufted pile fabric, embodying my invention.

Figure 2 is a front view of one end portion of the tuft yarn frame and a portion 40 of the row of yarn grippers which co-operate therewith.

Figure 3 is a front view of a portion of the tuft yarn frame, enlarged.

Figure 4 is a transverse section through 45 the tuft yarn frame, on line 4-4 of Fig. 8.

Figure 5 is a transverse section through the lower portion of the tuft yarn frame, on line 5-5 of Fig. 8.

Figure 6 is a rear view of a portion of a 50 part of the tuft yarn frame.

Figure 7 is a longitudinal section through a portion of the tuft yarn frame, on line 7-7 of Fig. 4.

Figure 8 is a bottom view of a portion of the tuft yarn frame.

Referring to the drawings 2 designates a tuft yarn carrier and 3 a row of yarn grippers.

Each yarn gripper comprises two jaws 6 and 8. The jaws 8 are pivoted on the jaws 6 to move thereon from the open position shown by full lines in Fig. 1 to the closed position shown by dot-and-dash lines therein. The jaws 6 are fixed on a shaft 9 in lateral spaced relation, as shown in Fig. 2. The shaft 9 is carried by end arms 10 projecting fixedly from a rockable shaft 11 which is mounted to turn in bearing on the loom frame, not shown, whereby the grippers may be raised and lowered to the position shown by full lines and to the position shown by dot-and-dash lines in Fig. 1.

The jaw 8 of each yarn gripper 3 is provided with an arm 12 the free end of which extends between two plates projecting from 75 a shaft 13 which is mounted to be rocked in the arms 10 whereby the yarn grippers may be opened and closed.

The mechanism for supporting and actuating these yarn grippers is the same as that shown and described in my previous Patent No. 1,594,605.

The tuft yarn frame 2 comprises a long body bar 14 having an arm 15 on each end thereof provided with means for connecting 85 it to a carrying chain 16. The arm 15 is also provided with means forming a bearing for the tuft yarn spool 17 carried by the frame 2.

In practice a large number of tuft yarn frames like the frame 2 are employed and carried by two endless chains and successively brought into the yarn delivery position in which the frame 2 is shown in Fig. 1. The mechanism for thus supporting and bringing 95 the tuft yarn frames into the yarn delivery position with relation to the yarn grippers 3 is well known by persons skilled in this art.

The body bar 14 of the tuft yarn frame 2 has secured to the bottom thereof a strip of 100

sheet metal 18 bent to form spaced parallel parts 19 and 20 which project downwardly therefrom and extend longitudinally of the bar.

- 5 The forward part 19 has a row of openings 21 therein and the rearward part 20 has a row of openings 22 therein corresponding in number with the openings 21 and in alinement therewith transversely of the bar 14.
- 10 Extending between the parts 19 and 20 and arranged within the openings 21 and 22 therein is a row of laterally spaced plates 23. These plates 23 extend forwardly from the part 19 and forwardly of the bar 14 and the forwardly extending portions of the plates form yarn passages 24 between them for the reception of the tuft yarn strands 25 delivered by the spool 17. The main bodies of the plates 23 form the side walls of the yarn passages 24 and forward and rearward displacement of the yarn strands 25 is prevented by forward and rearward laterally extending projections 26 and 27, respectively, between which the yarn strands pass.
- 15 A sensitive flat spring 28 is provided which extends longitudinally of the bar 14 and has its upper edge portion held in place by brackets 29 on the bar 14. The spring 28 is shaped in cross section as clearly shown in Fig. 4, and its lower free edge portion extends into openings 30 in the plates 23 adjacent to the forward projections 26 so that the yarn strands 25 will pass between the projections 26 and the spring 28 and the latter will exert sufficient pressure against the strands to retain them properly within the yarn passages 24.
- 20 The rearward ends of the plates 23 have projections 31 formed thereon which enter the openings 22 in the part 20 and which are adapted to engage the bottom walls of the openings to prevent downward displacement of the plates, and the plates 23 are retained within the openings 21 and 22 by a removable
- 25 rod 32 which penetrates the part 19 and the plates 23.
- 30 The openings 21 and 22 in the parts 19 and 20 are made wider than the thickness of the plates 23 to permit lateral movement of the plates therein, and the rod 32 is fitted to the openings in the plates through which it extends with sufficient looseness to permit the plates 23 to rock on the rod both vertically and horizontally.
- 35 Extending between the parts 19 and 20 and arranged within the openings 21 and 22 therein adjacent to the plates 23 is a row of flat bow springs 33, one for each plate. These springs 33 are shaped as clearly shown in the drawings and they are retained within the openings 21 and 22 by the removable rod 32 which extends through openings in the springs as illustrated. By withdrawing the rod 32 from the part 19 both the plates 23 and the springs 33 may be removed from the

openings 21 and 22 for repairs, replacements and for any other desired purpose.

The central portions of the springs 33 bear in one direction longitudinally of the bar 14 against the adjacent plates 23, and the end portions of the springs 33 bear in the opposite direction against the opposing walls of the openings 21 and 22 and thereby maintain the plates 23 normally against the opposite walls of the openings 21 and 22 in substantially uniform spaced relation with the spaces or yarn passages 24 between them opposite to or in registry with the yarn grippers 3, or substantially so, as shown in Fig. 2. It will now be understood that the springs 33 constitute a yielding means which maintains the plates 23 in the normal position shown in the drawings and that the plates 23 and particularly the forward portions thereof of forming the yarn passages 24 may yield laterally in either direction longitudinally of the bar within the limits allowed by the openings 21 and 22 when lateral pressure is applied to the plates, and that when such pressure is removed the springs 33 will return the plates to normal position.

Each time the yarn grippers 3 are raised to the position shown by full lines in Fig. 1, the jaws of the grippers enter the yarn passages 24 with the jaws 6 of the grippers forwardly of the yarn strands within the passages and with the jaws 8 of the grippers rearwardly of the strands; and thereafter the grippers are closed upon the yarn strands and lowered sufficiently to draw down below the plates 23 the required lengths of yarn strands for forming tufts, and thereafter the strands are cut directly below the plates and the cut lengths are lowered by the grippers to the position shown by dot-and-dash lines in Fig. 1 to be woven as tufts into the fabric being produced by the loom, all in the usual manner well known in tuft weaving.

The respective sides of the upper ends of the gripper jaws 6 and 8 are beveled and the bottom edges of the plates 23 are rounded so that if, for any reason, any or all of the grippers 3 should be out of registry with the yarn passages 24, and the grippers should engage any or all of the plates 23 when the grippers are moved into the yarn passages, the plate or plates thus engaged by the gripper or grippers will yield in a lateral direction and permit the grippers to enter the yarn passages without any damage whatsoever to either the grippers or the plates.

I claim as my invention:

1. A tuft yarn frame comprising a body bar provided with means for carrying a tuft yarn spool, a row of laterally spaced and laterally movable plates forming passages between them for yarn strands delivered from said spool, means connecting said bar and said plates, and spring means maintain-

ing said plates normally in predetermined positions and permitting them to yield laterally from such positions.

2. A tuft yarn frame comprising a body bar provided with means for carrying a tuft yarn spool and having a part provided with laterally spaced openings therein, a row of laterally spaced plates within said openings and forming passages between them for yarn strands delivered from said spool, said openings being wider than said plates and permitting lateral movement of the plates therein, spring means acting upon the plates and maintaining them normally in predetermined positions and permitting them to yield laterally from such positions, and means to retain said plates within said openings.

3. A tuft yarn frame comprising a body bar provided with means for carrying a tuft yarn spool and having a part provided with laterally spaced openings therein, a row of laterally spaced plates within said openings and forming passages between them for yarn strands delivered from said spool, said openings being wider than said plates and permitting lateral movement of the plates therein, flat springs adjacent to said plates yieldably maintaining them in predetermined positions, and a removable rod penetrating said part and said plates and said springs and holding them in operative relationship.

4. A tuft yarn frame comprising a body bar provided with means for carrying a tuft yarn spool and having spaced parallel parts projecting therefrom and extending longitudinally thereof, each of said parts having a row of openings therein alined with the openings of the other part transversely of the bar, a row of laterally spaced and laterally movable plates forming passages between them for yarn strands delivered from said spool and extending between said parts and into the openings therein, means to retain said plates within said openings, and bow springs extending between said parts and into the openings therein adjacent to said plates and yieldably maintaining them in predetermined positions.

5. A tuft yarn frame comprising a body bar provided with means for carrying a tuft yarn spool and having spaced parallel parts projecting therefrom and extending longitudinally thereof, each of said parts having a row of openings therein alined with the openings of the other part transversely of the bar, a row of laterally spaced and laterally movable plates forming passages between them for yarn strands delivered from said spool and extending between said parts and into the openings therein, bow springs extending between said parts and into the openings therein adjacent to said plates and yieldably maintaining them in predetermined positions, and a common means cooperating with one of said parts and hold-

ing said plates and said springs in operative relationship.

6. In a loom for weaving tufted pile fabric, a tuft yarn frame movable into and from a yarn delivering position and comprising a body bar provided with means for carrying a tuft yarn spool and carrying a row of laterally spaced and laterally movable plates forming passages between them for yarn strands delivered from said spool and being provided with spring means to maintain them normally in predetermined positions and to permit them to yield laterally from such positions, and means operable to move said frame to and from a yarn delivering position; in combination with a row of yarn grippers supported in fixed lateral spaced relation and movable into and from the spaces between said plates when said frame is in said yarn delivering position.

7. In a loom for weaving tufted pile fabric, a tuft yarn frame movable into and from a yarn delivering position and comprising a body bar provided with means for carrying a tuft yarn spool and having a part provided with laterally spaced openings therein, a row of laterally spaced plates within said openings and forming passages between them for yarn strands delivered from said spool, said openings being wider than said plates to permit lateral movement of the plates therein, spring means acting upon the plates to maintain them normally in predetermined positions and to permit them to yield laterally from such positions and means to retain said plates within said openings; and means operable to move said frame to and from a yarn delivering position; in combination with a row of yarn grippers supported in fixed lateral spaced relation and movable into and from the spaces between said plates when said frame is in said yarn delivering position.

8. In a loom for weaving tufted pile fabric, a tuft yarn frame movable into and from a yarn delivering position and comprising a body bar provided with means for carrying a tuft yarn spool and having a part provided with laterally spaced openings therein, a row of laterally spaced plates within said openings and forming passages between them for yarn strands delivered from said spool, said openings being wider than said plates to permit lateral movement of the plates therein, bow springs adjacent to said plates yieldably maintaining them in predetermined positions and a removable rod penetrating said part and said plates and said springs and holding them in operative relationship; and means operable to move said frame to and from a yarn delivering position; in combination with a row of yarn grippers supported in fixed lateral spaced relation and movable into and from the spaces between said plates when said frame is in said yarn delivering position.

between said plates when said frame is in said yarn delivering position.

9. In a loom for weaving tufted pile fabric, a tuft yarn frame movable into and from 5 a yarn delivering position and comprising a body bar provided with means for carrying a tuft yarn spool and having spaced parallel parts projecting therefrom and extending longitudinally thereof, each of said parts 10 having a row of openings therein aligned with the openings of the other part transversely of the bar, a row of laterally spaced and laterally movable plates forming passages between them for yarn strands delivered from 15 said spool and extending between said parts and into the openings therein and bow springs extending between said parts and into the openings therein adjacent to said plates and yieldably maintaining them in predetermined 20 positions; and means operable to move said frame to and from a yarn delivering position; in combination with a row of yarn grippers supported in fixed lateral spaced relation and movable into and from the 25 spaces between said plates when said frame is in said yarn delivering position.

In testimony whereof I affix my signature.

EUGENE F. CLARK.
